(57) **CLAIM**

The ornamental design for a retractable door bar, as shown and described.

DESCRIPTION

FIG. 1 is a front, top perspective view of a retractable door bar, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in an alternative position;

FIG. 10 is an enlarged view of detail "10" identified in FIG. 1;

FIG. 11 is an enlarged view of detail "11" identified in FIG. 1;

FIG. 12 is an enlarged view of detail "12" identified in FIG. 1;

FIG. 13 is an enlarged view of detail "13" identified in FIG. 1;

FIG. 14 is an enlarged view of detail "14" identified in FIG. 1;

FIG. 15 is an enlarged view of detail "15" identified in FIG. 2;

FIG. 16 is an enlarged view of detail "16" identified in FIG. 2;

FIG. 17 is an enlarged view of detail "17" identified in FIG. 2;

FIG. 18 is an enlarged view of detail "18" identified in FIG. 2;

FIG. 19 is an enlarged view of detail "19" identified in FIG. 2;

FIG. 20 is an enlarged view of detail "20" identified in FIG. 3;

FIG. 21 is an enlarged view of detail "21" identified in FIG. 4;

(Continued)

FIG. 22 is an enlarged view of detail “22” identified in FIG. 6;

FIG. 23 is an enlarged view of detail “23” identified in FIG. 7;

FIG. 24 is an enlarged view of detail “24” identified in FIG. 8; and,

FIG. 25 is an enlarged view of detail “25” identified in FIG. 8.

The retractable door bar is shown with a symbolic break in its length. The appearance of any portion of the retractable door bar between the dash dot dash symbolic break lines form no part of the claimed design. The dashed lines in the figures illustrate portions of the retractable door bar that form no part of the claimed design. The dash dot dash lines in FIGS. 1, 2, 3, 4, 6, 7, 8, 10, 11, 12, 13, 14, 15, 16, 17, 18, 19, 20, 21, 22, 23, 24 and 25 are for the purpose of illustrating the enlarged views indicators and form no part of the claimed design.
